MERCURY SWITCH RELAY

Carl H. Larson, Elkhart, Ind., assignor to The
Adlake Company, a corporation of Illinois

Application October 10, 1935, Serial No. 44,399

10 Claims. (Cl. 200—112)

The primary object of this invention is to provide a compact, readily accessible, and reasonably inexpensive mounting for mercury switch relays of the type in which a magnetically controlled plunger armature, moving in response to a relay coil, displaces more or less mercury within a switch envelope to change the condition of the electrical circuit through electrodes projecting into the envelope.

10 Other objects are to provide a mounting which facilitates inspection and minor repairs, permits switch elements to be changed without dismantling the entire relay, excludes dirt and dust from the relay unit, and prevents unauthorized access to the operating parts of the relay unit.

15 Further and other objects and advantages will become apparent as the disclosure proceeds and the description is read in conjunction with the accompanying drawings, in which

20 Fig. 1 is a side, elevational view of a relay embodying my invention;

Fig. 2 is a front, elevational view of the same;

25 Fig. 3 is a wiring diagram showing a circuit which may be used with the three coil unit shown in the illustrative form of the invention;

Fig. 4 is a transverse, sectional view through the relay taken on the line 4—4 of Fig. 6;

Fig. 5 is a horizontal, sectional view taken on the line 5—5 of Fig. 4;

30 Fig. 6 is a vertical, longitudinal, sectional view taken on the line 6—6 of Fig. 5; and

Fig. 7, 8 and 9 are views corresponding to Figs. 4, 5 and 6, respectively, but showing a modified form of the invention.

35 It will be understood that the disclosure of specific embodiments of the invention are for the purpose of complying with Sec. 4888 of the revised statutes, and the appended claims are to be construed as broadly as the prior art will permit.

40 The relay unit shown in the drawings is intended for shelf mounting. It comprises, in general, a base 10, a sub-unit 11 mounted on the base, and a cover 15. The sub-unit consists of three vertical coil units 12, 13 and 14, each of which includes a mercury switch of the type in which mercury is displaced by a magnetically controlled plunger to change the condition of the circuit through electrodes projecting into the switch envelope. This type of switch, broadly, is disclosed in Larson Patent No. 1,967,951, issued July 24, 1934.

45 The base 10 is preferably made of cast aluminum, and comprises side walls 16 and 17, rear wall 18, front wall 19 and top wall 20, the latter being reinforced by gussets 21 and 22 merging

5 into the rear wall 18. The top wall 20 has a relatively large longitudinal opening 23 adjacent to its forward edge in order to receive the lower ends of the mercury switches associated with the coil units 12, 13 and 14.

As will be seen by referring to Figs. 4 and 6 particularly, the base 10 is hollow and is provided at its four corners with bosses 24 which are drilled and tapped to receive machine screws 25 which secure a base cover plate 26 to the base. 10 Preferably, the plate 26 is lined with an insulator 27 to avoid any possibility of wires from the switches short circuiting through the cover.

15 The front portion of the base is inclined away from the main body of the relay and on this 15 inclined portion, a terminal block 28 of insulating material is adapted to be removably secured. The block is secured to the base by screws 29 two of them entering tapped holes in the corner bosses 24 and the other two entering tapped holes in 20 the other bosses 30. The block can, therefore, be easily removed for checking the wiring.

25 A plurality of terminal posts 31 are mounted on the terminal block 28, the heads 32 of the posts bearing against longitudinal ridges 33 25 formed on the block in order to keep the posts from turning when the binding post nuts 34 are screwed into place.

30 The base is mounted on rubber feet 35 secured to the base cover 26 by bolts and nuts 36.

35 The inclined terminal block has the advantage that it discourages careless workmen from laying tools on the posts and thereby short-circuiting the relay.

The sub-unit 11 comprises an L-shaped bracket 35 45 made of sheet steel and the coil units 12, 13 and 14 with their respective switches 46, 47 and 48 and their respective coils 49, 50 and 51. Each coil unit includes an iron magnetic circuit comprising a laminated yoke 52, the legs of which 40 abut against the ends of the switch associated with the unit. Tube clips 53 attached to the ends of the yoke embrace the switch and hold it within the coil subject to vertical adjustment by an adjusting device generally designated 54, comprising 45 a rod 55 vertically movable within a guide 56 attached to the yoke 52 and having its lower end extending through an opening 57 in the top wall 20 of the base 10. The end of the rod 55 is bent laterally and drilled to receive a clip 58 which 50 engages a bakelite sleeve 59 sealed on to the lower end of the mercury switch. The upper end of the rod 55 is threaded to receive adjusting nuts 60 and a spring 61 is interposed between the guide 56 and the laterally extending portion of the rod 55

55 so as to always hold the switch in its adjusted position within the relay.

A bracket 62 is used to secure the vertical coil units to the support bracket 45. See Figs. 4 and 5, particularly.

In assembling the sub-unit 11 to the base 10, the switches 46, 47, 48 and the adjusting devices 54 are first omitted from the sub-unit assembly and the latter is secured to the base with 10 screws 63. The switches 46, 47 and 48 are then put in place and the adjusting rods 55 inserted upwardly through the openings 57 in the top wall of the base. The nuts 60 are then screwed into place and the sub-unit is completely assembled 15 on the base.

The sub-unit is completely enclosed by the cover 15 which seats on a ledge 64 formed on the base, a cork or felt gasket being interposed between the cover and base to exclude dirt and dust.

20 The cover has a large opening 66 in its front face which receives a window 67 held in place by a retainer 68 secured to the cover by screws 69. The window 67 exposes the entire front portion of the sub-unit 11 to view.

25 The cover 15 is secured to the base 10 by screws 70 which engage studs 71 rising from the base. The cover 15 is preferably provided with recesses 72 where the screws 70 pass through the top wall of the cover in order that the surrounding 30 space may be filled with sealing compound to prevent unauthorized access to the interior of the relay.

35 In the form of the invention shown in Figs. 7-9 inclusive, the vertical coil units are similar to the ones shown in Hedin Patent No. 1,967,948 issued July 24, 1934, and the adjusting device, here designated 75, is alongside the switch 2. Each coil unit is secured to the support bracket by a pair of brackets 16, each of which is provided 40 with a keyhole slot for attachment to the support bracket. Except for the above mentioned changes, the relay is substantially the same as shown in Figs. 4, 5 and 6.

45 In Fig. 3, a circuit is shown for a relay of the type herein disclosed. The purpose of the relay when used with this circuit is to transfer a load 77 from its normal source of power (alternating current) to a secondary source of power (direct current) when the former fails for any reason, and to transfer the load back to the primary 50 source of power when it revives. The alternating current source of power is indicated at 78 and the direct current source at 79, and the former is connected to binding posts 80 and 81, the latter 55 to binding posts 82 and 83. The load 77 is connected to binding posts 84 and 85, and the remaining binding posts 86 and 87 are connected to the secondary of the transformer 88. The switch 47 is of the front contact type, i. e. the 60 circuit through the switch is closed when the associated coil is energized. This is indicated diagrammatically by the position of the plunger 89 (it being assumed that the coil 50 is energized).

65 The switches 46 and 48 each have three electrodes, one in contact at all times with the mercury and the other two only intermittently in contact with the mercury. The two intermittently immersed contacts are of different heights, 70 the shorter being within the plunger, and the longer being outside. The plunger 90 is closed at its top as indicated diagrammatically, and has a small opening 91 in its side wall just above the level of the mercury when the associated coils 75 49 and 51 are energized. When the plunger is in

this position, i. e. with the coils energized, the mercury in the switches covers the short electrodes and connects the load to the alternating current supply of power, but when this source of power for any reason falls below a predetermined 5 value, the coil 50 is de-energized and allows the plunger 89 to rise a sufficient distance to break the circuit through the switch 47. This de-energizes the coils 49 and 51 causing their respective plungers 90 to fall by gravity to a lower position. 10 As soon as the opening 91 reaches the mercury, the gas entrapped within the upper portion of the plunger forces the mercury away from the shorter electrode and simultaneously raises the mercury level on the outside, thus placing the 15 load 77 in circuit with the battery 79 and disconnecting the mercury from the alternating current source 78. When the current in the alternating current source is revived, the coil 50 pulls the plunger 89 downwardly and thereby energizes 20 the relay coils 49 and 51 and again places the load in the circuit with the alternating current source.

I claim:—

1. In a mercury switch relay, a hollow base 25 having a top wall provided with an opening extending along its forward edge, a sub-unit mounted on the top wall comprising an L-bracket and a plurality of vertical coil units attached to the bracket, a mercury switch associated with each 30 coil unit at least one of said switches projecting downwardly through the opening in the top wall of the base.

2. In a mercury switch relay, a hollow base 35 having a top wall provided with an opening extending along its forward edge, a sub-unit mounted on the top wall comprising an L-bracket and a plurality of vertical coil units attached to the bracket, a mercury switch associated with each unit at least one of said switches projecting 40 downwardly through the opening in the top wall of the base, and a switch adjusting device associated with the last-named switch.

3. In a mercury switch relay, a hollow base 45 having a top wall provided with an opening extending along its forward edge, a sub-unit mounted on the top wall comprising an L-bracket and a plurality of vertical coil units attached to the bracket, a mercury switch associated with each unit at least one of said switches projecting 50 downwardly through the opening in the top wall of the base, and a switch adjusting device associated with the last-named switch, said device including a rod vertically movable through an opening in the top wall of the base. 55

4. In a mercury switch relay, a hollow base having a top wall provided with an opening extending along its forward edge, a sub-unit mounted on the top wall comprising an L-bracket and a plurality of vertical coil units attached to the 60 bracket, a mercury switch associated with each coil unit at least one of said switches projecting downwardly through the opening in the top wall of the base, and a removable cover on the base 65 enclosing the sub-unit.

5. In a mercury switch relay, a hollow base having a top wall provided with an opening extending along its forward edge, a sub-unit mounted on the top wall comprising an L-bracket and a plurality of vertical coil units attached to the 70 bracket, a mercury switch associated with each coil unit at least one of said switches projecting downwardly through the opening in the top wall of the base, and a removable cover on the base 75 enclosing the sub-unit, said cover having a win-

dow in said forward wall exposing the sub-unit to view.

6. In a mercury switch relay, a hollow base having a top wall provided with an opening extending along its forward edge, a sub-unit mounted on the top wall comprising an L-bracket and a plurality of vertical coil units attached to the bracket, a mercury switch associated with each coil unit at least one of said switches projecting downwardly through the opening in the top wall of the base, a removable cover on the base enclosing the sub-unit, the relay base projecting beyond the forward face of the cover, and a terminal block carried by said projecting portion of the base.

7. In a mercury switch relay, a hollow base having a top wall provided with an opening extending along its forward edge, a sub-unit mounted on the top wall comprising an L-bracket and a plurality of vertical coil units attached to the bracket, a mercury switch associated with each unit at least one of said switches projecting downwardly through the opening in the top wall of the base, a switch adjusting device associated with the last-named switch, said device including a rod vertically movable through an opening in the top wall of the base, and a removable cover closing the bottom of the base.

8. In a mercury switch relay, a hollow base having a top wall provided with an opening extending along its forward edge, a sub-unit mounted on the top wall comprising an L-bracket and a plurality of vertical coil units attached to the bracket, a mercury switch associated with each unit at least one of said switches projecting downwardly through the opening in the top wall

of the base, a switch adjusting device associated with the last-named switch, said device including a rod vertically movable through an opening in the top wall of the base, a removable cover closing the bottom of the base, and a plurality of feet carried by said cover.

9. In a mercury switch relay, a hollow base having a top wall provided with an opening extending along its forward edge, a sub-unit mounted on the top wall comprising an L-bracket and a plurality of vertical coil units attached to the bracket, a mercury switch associated with each coil unit at least one of said switches projecting downwardly through the opening in the top wall of the base, a removable cover on the base enclosing the sub-unit, the relay base projecting beyond the forward face of the cover, and a terminal block carried by said projecting portion of the base, said terminal block being inclined away from the main body of the base.

10. In a mercury switch relay, a hollow base having a top wall provided with an opening extending along its forward edge, a sub-unit mounted on the top wall comprising an L-bracket and a plurality of vertical coil units attached to the bracket, a mercury switch associated with each coil unit at least one of said switches projecting downwardly through the opening in the top wall of the base, a removable cover on the base enclosing the sub-unit, the relay base projecting beyond the forward face of the cover, and a terminal block carried by said projecting portion of the base, said terminal block being inclined away from the main body of the base.

CARL H. LARSON. 35
